UNITED STATES PATENT OFFICE.

JOSEPH L. COX AND PAUL F. COX, OF BATTLE CREEK, MICHIGAN.

PRINTING PRESS AND FOLDER.

Application filed June 6, 1927. Serial No. 196,780.

This invention is an improvement in flat bed web printing presses and its principal object is to enable newspapers of more than 8 pages to be produced from two presses and 5 one folding mechanism; so that for instance, with two ordinary flat bed web printing presses each having a total capacity of eight newspaper pages, we can produce up to sixteen page newspapers, book-fold; or thirty- 10 two page tabloids, bookfold. This is accomplished by our novel method of and means for assembling and severing the webs before folding thereof.

Another object of the invention is to 15 simplify the web feeding and delivery devices by utilizing the male and female cutting cylinders as the delivery mechanisms for the sections of the respective webs, thereby insuring accurate register of the web sections and accurate cutting of the assembled 20 webs into sheets by one cutting mechanism, before folding of the webs; the combined products of the two presses being delivered through and by a single cutting and folding 25 mechanism, and enabling us to produce book-fold papers of any desired number of standard size newspaper pages from a minimum of two pages up to sixteen pages by twos; and also to produce book-fold tabloid size 30 papers from four to thirty-two pages as desired, by fours.

The invention is particularly designed for use with flat bed web presses such as shown in Cox Patent No. 1,457,501 dated June 5, 35 1923, but is useful with other styles of flat bed web printing presses.

Flat bed web presses are ordinarily capacitated to print eight newspaper pages, and such a press is ordinarily large enough for 40 the usual edition of the paper—but many publishers desire at times to produce larger papers and to do this with such a press they have to make two runs of the paper and produce such larger publications in two sections 45 and are compelled to stuff the two sections by hand. An eight page press is ordinarily fast enough, when but a single run is required; but where the pressroom time must be doubled by making double runs it causes 50 increased expense and frequent delays in the delivery of the said papers. There is therefore a demand for a flat bed press that will give a total product of up to sixteen pages in

one run, and deliver such a product book-fold in quarter page, or in mail size last fold. 55 Heretofore to meet the demand for larger papers, it has been attempted to use two flat bed presses and assemble their products; but it has proved almost impossible to keep the webs of two combined flat-bed web presses 60 running uniformly together so that they would reliably register at the cutting cylinders, and thus far it has not been practically possible to feed and deliver the webs of two flat-bed presses at the same and uniform 65 speed at all times as one or the other web will over-run or lead.

While in rotary presses the webs can be accurately associated, the action of the webs in flat-bed and reciprocating cylinder 70 presses is different, and the devices and methods of feeding, folding and cutting used in rotary presses is of little value in the operation of flat bed web presses.

After many efforts and experiments we 75 have finally discovered a simple, novel and useful arrangement and combination of presses and cutting and folding devices whereby the products of two flat-bed web presses can be reliably associated, delivered 80 and severed together in such manner that any inaccuracy of feed in one press or the other is readily accounted for and corrected by immediately severing the assembled webs before they are folded. 85

In the accompanying drawings we have diagrammatically illustrated one practical apparatus embodying the invention and will explain the same with reference to said drawings, to enable others to understand and use the invention: and we have summarized 90 the claims, the essentials of the invention and the novel features of construction and novel combinations of parts for which protection is desired. 95

In said drawings,—

Figure 1 is a rear end elevation partly broken away of two flat-bed web printing presses and a common cutting and folding mechanism arranged in accordance with our 100 invention;

Fig. 2 is a diagrammatic partial top plan view of Fig. 1;

Fig. 3 is an enlarged sectional view showing the male cutting cylinder and the disappearing knife, and its operating devices; 105

Fig. 4 is a detailed elevation of the cutting cylinders and co-acting devices.

P and P' represent two flat-bed reciprocating cylinder web perfecting presses constructed substantially as in the aforesaid Cox patent; but they may be of any other suitable construction, and print either on one or both strokes of the cylinders. These two presses are preferably arranged side by side but spaced apart sufficiently to permit a folding mechanism F to be interposed between them. Such folding mechanism is preferably arranged adjacent the drive end of the press. It is unnecessary to illustrate or describe such presses in detail, because the present invention relates to the means for assembling, delivering, cutting and folding the webs after they have been printed by such presses. The presses are usually adapted to print webs four news-paper pages wide. After such webs have been printed the web in each press is divided into two longitudinal web sections.

In the drawings the web printed by press P is divided into two sections w' and w^2 , by a slitter S. The web printed by press P' is divided by slitter S' into two longitudinal sections w^3 and w^4 .

Each section of the web (w' and w^2) coming from press P is given a quarter turn over an angle bar or guide (a^1 , and a^2) and led toward the folder between the presses. Similarly each section of web (w^3 and w^4) printed by press P' is given a quarter turn over an angle bar (a^3 , a^4) and led toward the folder between the press.

Mounted in the frame above the folder and between the presses is a pair of cutting cylinders, 1 and 2, whose axes are preferably disposed parallel with the longitudinal axes of the printing presses, and at right angles to the axes of the impression cylinders of said presses. Cooperating with the female cutting cylinder 1 is a roll 3, which may be geared to the cylinder 1 or driven by a frictional contact therewith or in other suitable manner.

Cooperating with the male cutting cylinder 2 is a web forwarding means, preferably comprising a series of coaxing tapes 4 running over a triangularly arranged series of rollers 4^a so disposed that portions of the tapes contact with the periphery of cylinder 2 and cooperate therewith to deliver the webs w^3 , w^4 to the cutting point. One of the rollers 4^a may be made adjustable for the purpose of varying the tension on the tapes 4, to regulate the pull or tension of the web sections w^3 , w^4 , drawn forward by the tapes 4 and cylinder 2.

As shown, the sections w' and w^2 of the web from press P are assembled by turning them over angle bars a^1 and a^2 and the assembled sections are led to and between the cylinder 1 and cooperating roll 3, which

act as a means for delivering such web section from the press P to and between the cutting cylinders 1 and 2.

Similarly the web sections w^3 and w^4 are assembled by turning them over the angle bars a^3 and a^4 , and such assembled sections are led to and between the cylinder 2 and tapes 4, which act as a means for feeding or delivering such associated webs to and between the cutting cylinders 2 and 1.

Adjustable web guides G may be provided for the web section w' , and similar guides G' may be provided for the web section w^3 so that the leading edges of the sections of the several webs will register when assembled. The web guides and all the sections are so disposed that the leading edges of all the sections w' and w^2 , w^3 and w^4 will register before they pass between the cylinders 1 and 2.

At each rotation of the cylinders 1 and 2 a sheet length is severed from each of the assembled web sections. This is preferably accomplished by means of a disappearing knife 5, which is mounted within and movable radially of cylinder 2, and is projected at the proper time to cooperate with the cylinder 1 and sever the webs, and is then retracted in cylinder 2 so that it will not interfere with the proper delivery of the webs by the cylinders.

The knife 5 may be operated by any suitable means. In Figures 3 and 4 the knife bar 5^a is shown as connected at its ends to guide rods 5^b which extend through diametrical bores or slots in the trunnions of the cylinder 2; springs 5^c on rods 5^b act to normally retract the knife 5 into the cylinder. The knife bar 5^a is provided at its ends with rollers 5^d which contact with the peripheries of cams 6 fastened to the framing adjacent each end of the cylinder 2; and said cams 6 are so shaped that the knife 5 will remain retracted within the cylinder 2 until the knife almost reaches the point of contact between the cylinders 1 and 2, and then the knife is projected so that it will coact with the slot in female cylinder 1 and sever the assembled webs, and then is retracted out of the way. This action takes place for and during each revolution of the cutting cylinders.

The assembled and severed sheets are then folded by any suitable means. Any suitable type of folder may be employed. Preferably we employ a folder having a plurality of folding rolls and tucker blades, the essential being that the webs are assembled and severed before the webs are folded; or in other words the webs are severed while the sections are all lying flat one upon the other; and the webs are not folded at the point of severance prior to the severing.

In the drawings we have indicated a folder having a pair of folding rolls 7 and 8

tucker blade 7^a adapted to fold the cut sheets to one-half size; and the thus folded sheets are then passed to and between a pair of folding rolls 8 by a tucker bar 8^a ; if desired 5 additional folding rolls and tucker blades may be provided to make any desired number of folds in the final product.

The presses, delivering and cutting cylinders and folders may be driven in unison by 10 any suitable means. As shown the two presses may be driven synchronously from a common drive shaft S carrying gears s , meshing with the main crank gears D of the respective presses. This same shaft drives 15 the folder by means of a pinion t , meshing with the gear T on the drive shaft of the folder. The cylinders 1 and 2 may be driven by means of a bevel gear U on the folder shaft meshing with a bevel gear v on a vertical shaft V which carries a bevel gear w 20 meshing with a bevelled gear 2^a on the shaft of cylinder 2 . In this manner both presses, the folder and the delivery cylinders can be driven synchronously.

25 It will be seen by reference to Figure 1 that the webs w' and w^2 from press P , pass to the left toward the cylinder 1 ; and the webs w^3 and w^4 from press P' pass to the right toward cylinder 2 . The sections of 30 web travel directly to and between the cylinders 1 and 2 but the webs from the two presses remain separated and independent, so far as the delivery is concerned, until they are severed, although their leading edges 35 meet as they pass into the bite of the cutting and delivering cylinders 1 and 2 .

By utilizing the peripheries of the cutting cylinders 1 and 2 as the major and controlling part of the web delivery means, we insure 40 that the webs will pass to the cutting point with absolute accuracy, and there is no tendency of sections of webs from one press to crowd past or hold back on the sections of webs from the other press, and there 45 is no tendency of one section of web to creep up on another, as occurs when all the sections are led over one roll, or fed by one feeding mechanism. In our invention the webs from one press do not have any influence 50 upon the webs from the other press. Each is handled entirely independent up to the point of cutting and only assembled sheets travel together through the folder.

Further in our invention all the web sections and all the sheets will be folded alike 55 in book form whether the presses are producing newspapers of two up to sixteen pages in size. Whatever the total capacity of the presses may be, and whatever the size 60 of paper being printed, the register of the printing and cutting points of the several web sections is maintained during the entire run of the press; because the web from each press is handled independently, and the 65 product of the two presses are not associated

until they meet at the cutting cylinders and the sheets are not folded until severed.

It has been heretofore attempted to operate two flat-bed presses together and assemble their products but while the continuously fed webs of both presses will travel apparently the same for a short while in a few minutes one or the other webs will commence falling back or travelling ahead of the other as the occasion may be. This variation is but very slight but when all the webs are tensioned and delivered together this variation augments until the webs from one press are so much out of register with the other that one set of webs will not be severed at the desired margin and the product is spoiled; many efforts and devices have been tried and have had to be discarded and abandoned in the effort to deliver all the web sections in book-fold.

With our invention any slightly inaccuracy of feed in the webs of either or both presses results in no bad results as each section of the web is cut off before folding at once and the errors are not allowed to multiply and a good product book-fold can be continuously produced.

In our invention any error in feed is compensated for at each revolution of the cutting cylinders and the webs maintain correct 95 spacing as they are practically handled by separate combined feeding deliveries; where if the webs of the two presses were all assembled and folded together before cutting the errors of feed would also accumulate.

Any infinitesimal difference disappears as the assembled webs are severed and go direct to the folding devices. As shown in the drawing the cutting cylinders are utilized as the out-feeding devices and the coaxing tapes enable us to keep the webs from press P' combed up to tension, and fed steadily to the point of severance without disturbing the webs from press P . By using a disappearing knife we are able to employ the cutting cylinders as the final web feeding mechanism for both presses; while the sections of webs from the separate presses come to the cutters in opposite directions. The female cylinder delivers the product of 105 press P ; while the Martin male cutting cylinder delivers the product of press P' —all the assembled webs being severed by the disappearing blade at the proper time. The sections of the web from both presses are 110 properly turned by the angle bars employed and spaced by the usual spacing and guiding rollers in the drawings; while the usual web compensating rollers can be used separately to bring the product of either press to proper 115 register for cutting, even when presses are in operation.

We claim:

1. In combination, a pair of flat-bed printing presses; a pair of cutting cylinders, one 130

of which is provided with a disappearing web severing device, and means co-acting with the cylinders whereby they assemble, sever and deliver the products of said presses.

2. In combination, a pair of flat-bed web printing presses, a pair of cutting cylinders, one of which is provided with a disappearing web severing device, and co-acting means arranged between the two presses whereby any and all products of the presses may be assembled and folded in book-fold, after the several strands of webs have been severed.

3. In combination, a pair of web printing presses; a pair of cutting cylinders, one of which is provided with a disappearing web severing device, means operating in connection with one cylinder to deliver the webs from one press; and means cooperating with the other cylinder to deliver the webs from the other press.

4. In combination with a pair of flat-bed web printing presses, a pair of cutting cylinders disposed between the presses, one of which is provided with a disappearing web severing device; and means for directing the webs from the opposite presses in opposite direction to said cutting cylinders, said cylinders operating to deliver and to sever the webs.

5. In combination, a pair of flat-bed web printing presses; means for delivering and severing the webs including a pair of cutting cylinders one of which is provided with a disappearing web severing device.

6. In combination, a pair of flat-bed web printing presses, a pair of cutting cylinders disposed between the two presses; and means for directing the sections of the oppositely running webs from the opposite presses to said cutting cylinders, said cylinders operating to separately deliver and simultaneously sever the webs, substantially as described.

7. In combination, a pair of flat-bed web printing presses; a pair of cutting cylinders, means operating in connection with one cylinder to deliver the webs from one press; and a set of coaxing tapes cooperating with the other cylinder to deliver the webs from the other press and whereby the webs may be properly registered before severing.

8. In combination, a pair of flat-bed web printing presses; a pair of cutting cylinders provided with a disappearing web severing device, and means co-acting with the respective cylinders to assemble the web sections from the respective presses and to sever and deliver the products of both presses to folding means whereby they may be delivered in book fold.

9. In combination a pair of flat-bed web printing presses; cutting cylinders; means coaxing with the male cutting cylinder to deliver the webs from one press; means co-

acting with the female cutting cylinder to deliver the webs from the other press; and means whereby sheet lengths are simultaneously severed from all the webs by said cylinders, so that all products of either or both the presses may be folded book-fold.

10. In combination a pair of flat-bed web printing presses, a pair of cutting cylinders arranged between the presses, angle bars for directing the sections of webs from the opposite presses to the cutting cylinders, said cylinders assembling the products of both presses and severing the assembled products of the presses and delivering the severed sheets in such manner that they may be folded book-fold.

11. In combination, a pair of flat-bed web printing presses, a pair of cutting cylinders arranged between the presses with the axes of the cylinders parallel with the longitudinal axes of the presses, means coaxing with the respective cylinders for drawing the sections of webs from the opposite presses to the cutting cylinders, and means carried by the cylinders for severing the assembled products of the presses and delivering the severed sheets in such manner that they may be delivered book-fold.

12. In combination a pair of flat-bed printing presses, cutting cylinders, means coaxing with the male cutting cylinder to deliver the webs from one press, and means coaxing with the female cutting cylinder for delivering the webs from the other press; said cylinders being provided with a disappearing cutting blade whereby a sheet length is severed from the webs at each rotation of the cylinders and all products of either and both presses may be folded book-fold.

13. In combination a pair of web presses, a pair of cutting cylinders, means by which the product of one press is advanced to the severing point by the rotation of the female cutting cylinder, and means by which the product of the other press is advanced to the severing point by the rotation of the male cutting cylinder; a sheet being severed from each assembled web section for each rotation of said cylinders; and means for folding the severed sheets book-fold.

14. In combination, a pair of web printing presses; a pair of cutting cylinders, means operating in connection with the female cylinder to sever the webs from one press; and a set of coaxing tapes cooperating with the male cutting cylinder to deliver the webs from the other press, whereby the webs may be properly registered before severing; a sheet being severed from each assembled web section for each rotation of said cylinders; and means for folding the severed sheets book-fold.

15. In combination a pair of web printing presses; a pair of cutting cylinders, means operating in connection with the female cyl-

inder to sever the webs from one press; and a set of coaxing tapes cooperating with the male cutting cylinder, to deliver the webs from the other press, whereby the webs may 5 be properly registered before severing; said male cutting cylinder being provided with a disappearing blade whereby a sheet is severed from each assembled web section during the rotation of said cylinders; and means 10 for folding the severed sheets book-fold.

16. In combination a pair of flat-bed web presses and reciprocating cylinders, a pair of cutting cylinders, angle bars to assemble the webs of each press and direct the assembled sections to the cutting cylinders; means 15 coaxing with the female cutting cylinder by

which the product of one press is advanced to the severing point, and means coaxing with the male cutting cylinder by which the product of the other press is advanced to the severing point, and a disappearing knife carried by the male cutting cylinder whereby a sheet is severed from each assembled web section during the rotation of said cylinders and before any folding of the web or sheets; and means for folding the severed sheets 20 25 book-fold.

In testimony that we claim the foregoing as our own, we affix our signatures.

JOSEPH L. COX.
PAUL F. COX.
